UNITED STATES PATENT OFFICE.

JESSE PRESCOTT, OF WEBSTER, MASSACHUSETTS.

GARBAGE-INCINERATOR.

1,086,854.

Specification of Letters Patent. Patented Feb. 10, 1914.

Application filed August 30, 1911. Serial No. 646,776.

To all whom it may concern:

Be it known that I, JESSE PRESCOTT, a citizen of the United States, and resident of Webster, in the county of Worcester and

5 State of Massachusetts, have invented an Improvement in Garbage-Incinerators, of which the following description, in connection with the accompanying drawings, is a specification, like letters on the drawings representing like parts.

This invention relates to incinerators of a type adapted for domestic installation and for use in hospitals and like public institutions for the incineration and consumption

15 of garbage and other miscellaneous refuse on the spot instead of requiring the same to be carted away at frequent intervals.

The invention provides a garbage receptacle adapted to consume garbage and like matter with or without auxiliary heating means, and with provision for a preliminary drying-out of the garbage during the interval that it may be left in the receptacle before burning.

25 More particularly, the invention consists in an improved construction of garbage holding receptacle and arrangement of circulatory flues therein of the type shown and claimed broadly in my copending application Serial No. 708,512, filed March 14, 1911.

Other features of invention relate to an improved burner arrangement in connection with the flue construction, to a novel arrangement of the doors, and to other detail 35 matters which will hereinafter more fully appear.

The invention will be better understood from the following detailed description, taken in connection with the accompanying 40 drawings, and will be thereafter pointed out in the appended claims.

Referring to the drawings, Figure 1 is a central vertical section of one form of the invention, a portion being broken away; 45 Fig. 2 is a fragmentary plan showing the sectional vertical grate top, this being partly in section; Fig. 3 is a fragmentary horizontal section on line 3—3 of Fig. 1; Fig. 4 is a fragmentary section on line 4—4

50 of Fig. 1; Fig. 5 is a fragmentary vertical section on line 5—5 of Fig. 2; Fig. 6 is a central vertical section of another form of the invention; Fig. 7 is a fragmentary front view of the lower ventilating door; Fig. 8 55 is a horizontal section on line 7—7 of Fig. 6; and Fig. 9 is a section showing the inter-

locked arrangement of the doors when opened to clean out the receptacle, this section being taken on line 8—8 of the dotted line portion of Fig. 8.

Referring first to Figs. 1 to 5 the receptacle as shown is of a rectangular upstanding form with an inner casing 1 and an outer shell 2 spaced apart therefrom, the lower portion of the inner casing being enlarged from an intermediate shoulder 3 on downward to provide greater holding capacity in the receptacle. A suitable base 4 is provided, this having a flat bottom to receive an ash pan 5. Formed at one side of this bottom portion of the receptacle is an opening 6 of a size to permit removal of the ash pan and this is normally closed by a door 7. This door is formed as a skeleton frame having the central portions fitted with a fine mesh screen 8 to permit entrance of air for circulation up through the garbage mass as more particularly explained further on. A flat horizontal grate 9 rests on a ledge 9' projecting inwardly from the inner casing at a lower portion thereof, and this grate has a series of radial slots 10 and a central aperture 11 to receive the central gas burner. This horizontal grate has inter-fitted with its peripheral portion an open-work vertical grate 12 engaged with the bottom grate by having lugs 13 thereon extending into apertures 14 in the bottom grate and the grate 12 thence extends vertically upward with a top flange 15 to fit against the walls of the inner casing at the inner extremity of the shoulder 3. This vertical grate is generally rectangular in form and spaced away from the walls of the inner casing but its corners are flattened to lie in spaced apart relation to the corner flue plates 18 to be later described. This vertical grate has a series of openings 16 extending substantially throughout the height thereof and is preferably formed in a number of sections shown as four, the divisional lines being indicated at 17. By virtue of this construction this vertical grate can be readily removed from the receptacle for cleaning or other purposes as required.

Vertical flues are provided to extend up through the receptacle and in order to leave practically the entire interior of the receptacle unobstructed, I form these flues by fixing plates 18 diagonally across the corners of the casing. These plates at the shoulder 3 of the inner casing are sloped outward as

seen at 19 so as to fit the corners of the enlarged lower portion of the casing as at 20. The flue plates 18 have formed in their sloping portions 19 adjacent the top of the vertical grate 12 slot openings 21 which, it will be observed, are protected from being clogged up, both because they are under the shoulder 3 and because the top flange 15 of the grate extends around the casing just 5 above them. Other openings 22 may be formed at intervals along the height of these plates. A gas burner 23 is fitted to the central aperture 11 of the bottom grate and is formed with an upwardly diverging conical 10 portion 24 having a series of burner openings 25 therein, and thereabove with an upwardly converging cone top 26 extending well up into the receptacle. This cone top has a downwardly and outwardly extended 15 shroud or baffle 27 depending down below the burner openings 25 and adapted to divert the flame therefrom downwardly and outwardly so that it is thence directed and drawn to encompass the bottom and sides 20 of the garbage mass. The burner may be supplied with gaseous fuel by a connector pipe 28 having any desired form of mixer attachment 29 at the casing entrance. A suitable exit flue or stack connection 30 is 25 formed in the upper part of the apparatus to have joined thereto any suitable stack.

Referring to Fig. 6, the inner and outer casings 1', 2', are generally similar to the form just described with a similar base 4', 30 ashpan 5' and lower ventilating door 7'. This form likewise has substantially similar corner flues formed by plates 18' having at 35 intervals in the height thereof slot openings 22'. In this form, a ledge support 31 is fixed 40 in the lower portion of the casing, and on this rests a back fixed grate portion 32 and a front swinging grate portion 33, this swinging portion being shown as of somewhat larger extent than the fixed portion, 45 and hinged at 34 so as to drop downward to permit dumping of the grate when the rest pin 35 is pulled out by means of its outwardly extending knob 36 so as to release the front edge of the grate. The pivotal 50 axis 34 may be extended through the casing, with a squared end 34^a to receive an operating handle. Directly over this grate is a ring burner 37 having a series of burner holes 38 pointing inward, this ring burner 55 having a suitable inlet connection 39. This ring burner extends around in close proximity to the walls of the casing as shown, and is protected by an outwardly flaring annular baffle plate 40 which fits the inner walls of the 60 casing and the plates 18' and thence slopes downwardly inward well over the ring burner. The flue plates 18' extend down to this annular baffle or below it, and the lowermost of the slot openings 22' are only a 65 short distance above this baffle, as shown.

An important feature of the invention relates to a novel arrangement of the registering doors which are fitted to the inner casing and outer shell; and, while these may be arranged on either form of the invention, they are shown more completely in Figs. 6, 8 and 9. A single inner door 41 is mounted on a horizontal pivot 42 near the bottom of the garbage holding portion of the receptacle to cover an opening 43 in the inner casing of 70 the receptacle, and has a pivoted latch 44 at its top to engage a fixed catch 45. The outer shell has an opening 46 registering with the opening 43, and this is closed by two doors 47, 48 mounted on vertical pivots 75 49, 50 on the outer shell. The inner door 41 has at its sides downwardly extended flanges 51 adapted to take over and interlock with lugs 52 extending inwardly and upwardly from the bottom of the outer 80 doors 47, 48 when the doors are opened, thus forming a tight chute through which the ashes and residue of the burning may be raked from the receptacle into an ash can for removal. It is to be noted that 85 no special manipulation or effort is required for thus interlocking the inner door 41 with the outer doors 47, 48 to form this chute but that, as the outer doors are opened and the inner door swung down, 90 its flanges 51 automatically interlock with the lugs 52 which furnish a reliable support therefor and at the same time hold the outer doors which form the sides of the chute from opening farther to spread 95 away from their co-operative position in forming the chute.

As a means for the introduction of garbage to the receptacle, a swinging chute door 53 is pivoted at 54 near the top of the casing, this having an inner skeleton wing 55 joined to a closing plate 56 by the side plates 57. The closing plate 56 has mounted thereon in spaced apart relation thereto a baffle plate 58, this being, as shown, 105 cupped out for its peripheral flange to be fitted against the plate 56. The peripheral flange of this baffle plate is preferably recessed out or cut away so as to leave supporting lugs 59 at intervals, with intervening spaces so as to permit free circulation of air between the baffle plate and plate 56, 110 so that the baffle plate is kept cool. A suitable handle 60 is fixed to the baffle plate 58.

In use, the more combustible forms of 115 refuse may be burned in the receptacle without the aid of the gas burner, particularly if the material to be burned be left some little time to dry out. For this purpose, and whether the gas flame is to be used finally 120 for initiating the combustion or not, the ventilating lower door is of special importance in that it permits currents of air to enter at the bottom of the casing and to be drawn up through the refuse mass to 125 130

rapidly dry out the same, the corner flues 8 cooperating for this air draft effect, while at the same time the fine mesh 8 for covering the door openings prevents the entrance of insects and vermin which might otherwise be attracted by the contents. The receptacle having been partly or wholly filled with garbage of a nature requiring the aid of the gas burner for its consumption, the 10 annulus of flame from the circular series of burner openings 25 is projected downwardly and outwardly through the openwork grate and up the vertical sides of the grate portion 12, in the form shown in Fig. 1. By 15 reason of the spaced apart relation of the vertical grate 12 to the inner casing and arrangement of the flue openings 21 so as to be protected from clogging up by the flange 15 and the shoulder 3 as described, gaseous 20 products of combustion from the start find a relatively restricted but sufficient outlet down through or along the bottom grate 10 and up the annular space between the vertical grate 12 and the inner casing, and thence 25 through the openings 21 up into the corner flues, thus encompassing and impinging upon all exposed portions of the garbage mass through the openwork construction of the grates. As the garbage becomes dried 30 out with a corresponding shrinkage in mass, and the combustion thereof commences, the gradual increase in flue passages required is provided by the increasing opening of the lower portions of the flue opening 16 out 35 into the surrounding annular space and thereafter by the uncovering of the upper holes 22 in the corner flues if the garbage mass extends up that way. Thus the flue passages are more or less closely proportioned to the draft requirements and the extent of combustion so that an effective draft 40 is at all times created. It is to be understood that the conical cap 26 extending up into the center of the garbage mass and being heated to a high degree by the gas flame underneath, materially aids in the initial drying out of the central portion of the garbage mass. In the form shown in Fig. 6, the annulus of flame is first directed inward from 45 the ring burner, converging to the central portion of the garbage mass, but, as the flue openings which it must find for its initial escape are the lowest openings 22' into the corner flues near the bottom of the garbage 50 mass, it follows that the flame and heated currents will again work their way and eat through the garbage mass outward, thus quickly heating and drying all portions thereof, the initial inward impetus of the 55 flame causing the heat to reach the central portions of the mass, while the outward draft of the corner flues again disseminates and spreads the heat to the peripheral portions. The vertical grate 12 is formed in 60 a convenient number of sections to be 65

readily removed through the door openings 43, 46 and, upon the removal thereof, the receptacle space can be quickly and easily cleaned out, this operation being facilitated by the interlocking construction 70 of the side and bottom doors as before described. While all of the several features of the invention are thus interrelated and mutually contribute to produce a particularly efficient and practical incinerator, it 75 is to be understood that certain of said features are useful and valuable in other relations, and the particular association of parts shown, as also the specific construction of the several elements, is to be understood as illustrative and not restrictive, and it is further to be understood that the use of terms in the foregoing description is not intended to limit the invention in any particular except as set forth in the 80 appended claims. 85

Having described my invention, what I claim as new and desire to secure by Letters Patent is:

1. An apparatus of the kind described, 90 comprising an upright angular casing having corner flues formed therein, means for holding garbage in the lower portion of said casing, including a sectional vertical grate member spaced apart from the casing 95 about the periphery thereof, said casing being drawn inwardly adjacent the top of said vertical grate, and said corner flues having up-and-down openings leading directly into the annular space around said vertical grate 100 arranged to be protected from clogging up when the apparatus is filled with garbage.
2. An apparatus of the kind described, 105 comprising an upright receptacle formed with spaced apart inner and outer walls with registering openings, a grate in the lower portion of said receptacle, a door for the inner wall opening pivoted on a horizontal axis, and a door for the outer wall opening pivoted on a vertical axis, said doors being formed and arranged to interlock when in opened position to provide a 110 clean-out chute.
3. An apparatus of the kind described, 115 comprising an upright receptacle formed with spaced apart inner and outer walls with registering openings, a grate in the lower portion of said receptacle, a door for the inner wall opening pivoted on a horizontal axis, and a pair of doors for the 120 outer wall opening pivoted on vertical axes at the sides of said opening, said pair of doors and the inner door having portions arranged to interengage when in opened position to form a clean-out chute. 125

4. An apparatus of the kind described, 130 comprising an upright receptacle formed with spaced apart inner and outer walls with registering openings, a grate in the lower portion of said receptacle, a door for

the inner receptacle opening pivoted on a horizontal axis, a door for the outer receptacle opening pivoted on a vertical axis, said doors being out of engagement leaving 5 said space free when the doors are closed, and means on said doors arranged to automatically interlock when the doors are opened and hold the outer receptacle door in engagement with the inner receptacle 10 door, whereby said doors form a clean-out chute.

5. An apparatus of the kind described, comprising an upright receptacle formed with spaced apart inner and outer walls 15 with registering openings, a grate in the lower portion of said receptacle, a door for the inner receptacle opening pivoted on a horizontal axis, and a pair of doors for the

outer receptacle opening normally entirely disengaged from said first mentioned door 20 and pivoted on vertical axes at the sides of said opening, said vertically pivoted doors having inwardly extending lugs and said inner receptacle door having flanges arranged to automatically interlock with said lugs when the doors are opened to hold the doors rigidly assembled as a clean-out chute 25 when thus opened.

In testimony whereof, I have signed my name to this specification, in the presence of two subscribing witnesses.

JESSE PRESCOTT.
